BRICK CLEANING APPARATUS

BACKGROUND OF THE INVENTION

1. Field of the Invention

The invention pertains to brick working. More particularly it pertains to dressing of use bricks to remove adhering old mortar from them so that the bricks can be used again in new construction.

2. Prior Art

These currently exists a desire for used bricks as building material for new construction. Such bricks are preferable, for example, in colonial reconstruction or pseudocolonial construction. They are often particularly desirable because they contain natural earth colors not found in new bricks. However, salvaging such bricks from demolition projects is difficult because of the labor involved. It is, of course, necessary to remove the old mortar from these bricks before they can be used again. This is customarily done manually with chipping hammers and a large percentage of brick is lost because they are fractured by a hammer blow.

There have been some proposals for machines to clean bricks. These include, for example, that disclosed in U.S. Pat. No. 89,263 where bricks are forced between a pair of corrugated rollers; in U.S. Pat. No. 547,746 which also utilizes cleaning rollers and in U.S. Pat. No. 782,324 which utilizes abrasive discs. Grinding rolls are used in U.S. Pat. No. 1,505,867 and toothed rolls with saw blades in U.S. Pat. No. 3,087,483.

Despite these proposals, the work is done today manually with no tool more sophisticated than a hammer. Such procedures are hardly consistent with the advanced technology which is the provide of this country. Often, because of the cost of such manual labor, bricks are discarded and used as fill rather than salvaged.

SUMMARY OF THE INVENTION

The invention comprises an apparatus for removing mortar from a used brick and thus reclaiming it. The novel theory reflected in the apparatus involves delivering a series of blows across the mortar-covered surface or surfaces of the brick. These blows are sharp, have a uniform force and a fixed periodicity. Further, they are delivered with an arcuate component of force in a fixed linear locus of impact while the brick is held in a plane across which the locus lies. As the mortar disintegrates, the brick is advanced in the plane so that the locus progresses from one end of the brick to the other and it is sequentially stripped of its mortar.

Preferred apparatus is a striker having a square cross section which is rotated at a uniform speed about a fixed axis of rotation. Means such as a chute or conveyor may also be provided for passing one or more bricks proximate the striker in a plane contacted by all of its corners as rotation occurs.

It is also an object of the invention to provide an apparatus for removing mortar from bricks quickly and cheaply which is rugged in construction, adapted for portability to a job site, easy to operate, low in cost and easily repaired.

These and other objects of the invention will be apparent to those skilled in the art from a consideration of the description which follows.

BRIEF DESCRIPTION OF THE DRAWING

In the drawing, wherein like reference numerals designate like parts:

FIG. 1 is a diagrammatic sectional representation of the method of the invention.

FIG. 2 represents a perspective view of an apparatus embodying the invention.

FIG. 3 represents a fragmentary perspective view of a striker which may be used in the apparatus of FIG. 2.

FIG. 4 represents a fragmentary perspective view of another striker which may also be used in the apparatus of FIG. 2.

FIG. 5 represents a perspective view of another apparatus embodying the invention.

DESCRIPTION OF THE PREFERRED EMBODIMENTS

The method of the invention may be explained with reference to FIG. 1, which is a diagrammatic section. In the figure, a used brick, generally 10, is shown which has ends 11 and 12 and a face 13 to which is adhered old mortar 14. It is desired to remove mortar 14 from the brick without breaking it.

This is done by holding the brick in a fixed plane (horizontal, as shown) and striking the mortar with a series of sharp blows at a fixed linear locus of impact 15, on surface 13, which extends linearly across the plane and, thus, across the face of the brick. These blows may be delivered with the corner of a bar or with a striker, generally 16. However, it is critical to the method that these blows be delivered with a fixed periodicity, with a uniform force and with a component which is arcuate with respect to surface 13.

This may be done manually, but the necessary uniformity of force and evenness of rhythm, as well as the arcuate quality necessary if the brick is not to break is more easily achieved by rotating striker 16 about a fixed axis 17. The striker must have a plurality of corners 18, each equidistant from axis 17 in order to achieve the desired periodicity of impact and to deliver a series of glancing blows along line 15. Such a requirement is most easily achieved by providing the striker with a square cross section as shown. Direction of rotation of the striker is indicated by the arcuate arrow.

As the mortar disintegrates under the rain of blows, the brick is advanced in the direction shown by the straight arrow so that impact line 15 moves down the face 13 toward end 11. Relative motion may also, obviously, be achieved by leaving brick 10 in the position shown and moving axis 17 in a plane parallel to the face 13 so that locus 15 moves down the brick.

Although not essential, it is preferred to hard surface the leading edges 19, of corners 18 with a material harder than the balance of the striker. One suitable technique is to lay down a bead of welding rod containing 11-14 percent manganese. Other hard surfacing alloys are equally suitable for deposition and result in longer tool life.

In FIG. 2, an apparatus embodying the invention is shown. The striker portion is the same as striker 16 and is numbered accordingly.

The apparatus includes a frame 20 on which is mounted a gasoline or electric mortar 21 which drives a sheave 22. A belt 23 drives another sheave 24 mounted on a mandrel shaft 25 which is journaled through a bracket 26 mounted on frame 20. Striker 16 is mounted on a cantilevered extension of shaft 25 in a suitable manner. Motor speeds are chosen and sheaves are sized so that the striker rotates at suitable speeds, preferably in the range of 500 to 1,500 r.p.m.

To use the apparatus of FIG. 2, the operator holds a brick with a mortar-encrusted surface in a plane wherein it will be contacted by all corners 18 of rotating striker 16 and then advances the brick progressively in that plane to remove the mortar. He may then turn the brick and treat another surface in a similar manner.

FIG. 3 represents a striker which is not hard surfaced and FIG. 4 represents a striker which has two hard surfaces 30 and 31, at each corner 18. Such a tool can be utilized in one direction of rotation (e.g., until surfaces 30 wear) and then rotation can be reversed so that fresh surfaces 31 are utilized.

The apparatus shown in FIG. 5 is generally identical to the apparatus of FIG. 2 in terms of its frame, striker and striker rotating means. However, it is provided with adjustable chutes for one or more rows of bricks.

As shown, a chute 40 adjustably mounted on frame 20. This chute includes sidewalls 41 and 42; a bottom 43 and an intermediate dividing wall or septum 44. The bottom 43 is in a plane which is parallel to a plane tangent to the circle described by corners 18 as the striker 16 rotates, and is spaced apart from that plane by the thickness of a clean brick. Bricks 45, placed in the chute, feed by gravity to the striker where the mortar is removed. The operator is freed from guidance of the bricks and spends his time loading and unloading the machine.

Although the invention has been described in considerable detail, such description is intended to be illustrative rather than limiting since the invention may be variously embodied. Consequently, its scope is to be determined by the appended claims.

I claim:

1. Apparatus for removing adhering old mortar from used bricks comprising:
  - a. a frame;
  - b. a striker extending outwardly from said frame, said striker being square in cross section; and
  - c. means for rotating said striker at a uniform speed about a

fixed axis.

2. The apparatus of claim 1 wherein the mortar impacting surfaces of said striker, proximate the corners thereof, are harder than the balance of said striker.

3. The apparatus of claim 1 which further includes means for passing a brick proximate said striker in a plane contacted by all corners thereof as it rotates.

4. The apparatus of claim 3 wherein the mortar impacting surfaces of said striker, proximate the corners thereof, are harder than the balance of said striker.
